UNITED STATES PATENT OFFICE.

WILLIAM F. SCHADEL, OF CHARLESTON, WEST VIRGINIA, ASSIGNOR TO KANAWHA MANUFACTURING COMPANY, OF CHARLESTON, WEST VIRGINIA, A CORPORATION OF WEST VIRGINIA.

VIBRATORY SCREEN.

Application filed May 25, 1926. Serial No. 111,596.

This invention relates to vibratory screens and more particularly to improved means for vibrating a screen, an object of the invention being to provide means of this character which are adapted for screening any material which may be susceptible of grading by screening, such as coal, gravel, concrete aggregates, sand, grain, etc.

A further object is to provide a mechanism of this character which has relatively few parts and in which the working parts are enclosed rendering them substantially dustproof.

A further object is to provide mechanism of the character stated which requires a minimum of space for installation, which is strong and durable in use, and which most efficiently performs the functions for which it is intended.

With these and other objects in view, the invention consists in certain novel features of construction and combinations and arrangements of parts, which will be more fully hereinafter described and pointed out in the claims.

In the accompanying drawings—

Figure 1 is a perspective view, illustrating my improved apparatus;

Figure 2 is a view in transverse section 30 through the apparatus, taken on the line 2—2 of Figure 3;

Figure 3 is a view in longitudinal section of the apparatus;

Figure 4 is a fragmentary view in transverse section on the line 4—4 of Figure 3.

1 represents the supporting frame of my improved apparatus which supports an inclined chute 2, with a pair of side bars 3 above the chute and preferably of channel iron. Between these side bars 3 a screen 4 is located and is fixedly secured at its ends. To the side bars 3 inwardly projecting strips 5 are secured and overlie the screen so as to prevent the material from falling laterally off of the screen.

My invention has particularly to do with the means for vibrating the screen, and I provide a support for this means which includes a pair of transversely extending bars 6 which may be of angle iron, as shown, and which are secured to the upper edges of the side bars 3. Bearing brackets 7 are also secured to the side bars 3 between the bars 6 and provide rotary mounting for a shaft

7 extending transversely of the screen and 55 at the desired distance above the same.

8 represents a housing which has integral webs 9 supported upon and secured to the bars 6. The upper portion of this housing consists of a removable cap 9', and said cap 60 and housing proper constitute an enclosure for a cam 10 which is keyed to the shaft 7, and which has on its outer face an annular series of cam faces, as clearly illustrated.

The lower end of the housing 8 is rectangular, as indicated at 11, and is located in alignment with a casing 12, said portion 11 and casing 12 having annular flanges 15 and 14, respectively, which are secured together 70 in any approved manner.

The casing 12 has a central guide sleeve 16 with a bushing 17 therein, and a rod 18 is mounted to slide and reciprocate freely in said bushing. On the rod 18 within the 75 casing 12 a head or enlargement 19 is provided with a bifurcated bracket 20 constituting a part thereof and supporting a roller 21 which engages the periphery of the cam 10. A coil spring 22 is located in the casing 80 12 around the sleeve 16 and exerts upward pressure on the head or enlargement 19 holding the roller in contact with the cam 10.

The portion 11 of the housing 8 is angular in cross section, and the bifurcated bearing 85 bracket 20 is also angular in end elevation so as to prevent any tendency of turning movement of the rod 18. This rod 18 projects through the casing 12, and is screw-threaded.

The screen 4 has secured to its under face a transverse bar 23, and this bar and the screen are perforated to receive the lower end of rod 18. A nut 24 is located on the threaded rod 18 and screwed downwardly 95 against the screen, and another nut 25 is located on the rod and screwed against the bar 23, so that by the adjustment of these nuts the screen is firmly secured to the vibrating mechanism.

The casing 12 has a depending extension or apron 26 which extends part way around the same and prevents the particles from contact with the rod.

The operation is as follows:

It is of course to be understood that the shaft 7 may be driven from any suitable source of power, and when revolved the cam

10 thereon will impart rapid reciprocating or vibrating motion to the rod 18, which will be imparted to the screen 4 so that the material moving over the screen will be shaken 5 through the mesh of the screen or will roll down over the screen in accordance with the size of the particles.

10 Various slight changes and alterations might be made in the general form of the parts described without departing from my invention and hence I do not limit myself to the precise details set forth but consider myself at liberty to make such slight changes and alterations as fairly fall within the 15 spirit and scope of the appended claims.

I claim:

1. An actuating mechanism for vibratory screens, including a support adapted to be positioned above a screen, a housing fixed to 20 said support, a cam in said housing, means for turning the cam, a casing secured to said housing, a rod movable through the casing

and adapted to be fixed to the screen, a roller on the rod operated by the cam, a member adapted to be fixed to the lower face of the 25 screen and through which member the said rod projects, and nuts on the rod engaging the member and the screen whereby the screen is firmly secured.

2. An actuating mechanism for vibratory 30 screens, including a support, a housing, webs on the housing fixed to the support, a shaft projecting through the housing, a cam on the shaft in the housing, a casing secured to the housing, a central bearing sleeve in 35 the casing, a rod movable in said sleeve, a bracket on the rod, a roller in the bracket engaging the cam, a spring in the casing around the sleeve and exerting pressure on the rod in a direction toward the cam, and 40 means adapted to secure said rod to the screen.

WILLIAM F. SCHADEL.
